TREAD PLATE

John Schmeller, Sr., Lakewood, Ohio, assignor of
one-fourth to John L. Schmeller, Lakewood,
Ohio, one-fourth to Edward A. Schmeller, Lake-
wood, Ohio, and one-fourth to Frank L.
Schmeller, Rocky River, Ohio

Application December 5, 1938, Serial No. 244,927

9 Claims.

(Cl. 94—5)

This invention, as indicated, relates to a tread plate. More particularly, it comprises a composite plate adapted for a wide variety of uses, wherein a non-slipping surface is desirable, as well as a long period of service life. More particularly, the invention relates to a plate wherein material having abrasive characteristics as well as a high degree of hardness is embodied in a plate formed of relatively soft metal, particularly aluminum or aluminum alloys. It has been found that aluminum and aluminum alloys and the like, when combined with material such as carborundum or similar abrasive products, is exceptionally adapted for holding such abrasives in firm engagement throughout the period of use of the wear plate and found that at no time during the service life of the plate is there a tendency to develop smooth slippery surfaces over all or any portion of the plate. It has been found that the rate of wear of the aluminum is sufficiently greater than the rate of wear upon the abrasive substance to maintain a slight projection of such abrasive material above the surface of the aluminum area of the plate, so that at all times there is presented an abrasive tread surface to prevent slipping upon such surface. It has also been found that plates formed in the manner hereinafter set forth have wear edges particularly adapted to resist being worn to a dangerous smoothness which is so frequently the cause of accidents on tread plates intended for heavy traffic.

The principal object of the present invention is to form an improved tread plate or plate with a non-slipping surface wherein abrasive surface is provided and maintained throughout the service life of such plates.

Another object of the invention is to provide a tread plate or non-slipping surface of such character that high speed production may be carried on with absence of defects such as porous areas over the product and with uniform distribution of the abrasive material embodied in such product.

Another object of the invention is to provide a wear plate adapted for heavy service conditions and having exceptional capacity to resist wear.

Another object of the invention is to provide wear plates having substantially uniform distribution of abrasive material throughout the area of the plate and having the metal forming the body of the plate free of porous and defective areas.

Another object of the invention is to provide a wear plate having abrasive material distributed

throughout the body of the plate and exposed at the corner edges thereof uniformly in such manner that such edges will not wear to a smooth surface and wherein the plates through reversing may provide four wear edges before the plate is finally discarded.

Other and further objects of the invention will appear in the course of the following description.

To the accomplishment of the foregoing and related ends, said invention, then, consists of the means hereinafter fully described and particularly pointed out in the claims, the annexed drawing and the following description setting forth in detail certain structures embodying the invention, such disposed means constituting, however, but several of various forms in which the principle of the invention may be used.

In said annexed drawing:

Figure 1 is a central vertical sectional view showing a sand mold having a wear plate structure and multiple sprues associated therewith;

Figure 2 is a perspective view of the wear plate and accessory metal used in forming the same as it appears when removed from the mold shown in Figure 1;

Figure 3 is a fragmentary perspective view showing a section of the finished wear plate wherein small particles of abrasive material are distributed throughout the body of the plate.

Figure 4 is an enlarged view of the plate shown in Figures 2 and 3, wherein small particles of abrasive material are utilized, such view being taken along the line 4—4 shown in Figure 2, looking in the direction of the arrows;

Figure 5 is a view similar to Figure 4, wherein larger particles of abrasive material are utilized, such particles extending completely through the plate in a vertical direction;

Figure 6 is a perspective view of a modified type of wear plate wherein pre-formed composite blocks of abrasive material are united by a grid of relatively soft metallic material;

Figure 7 is an enlarged sectional view showing the elements of the structure illustrated in Figure 6, as seen along the line 7—7, looking in the direction of the arrows; and

Figure 8 is a view similar to Figure 7 showing a modified form of construction.

As is clearly shown in Figures 1 and 2 of the drawing, the plate 1 is formed of a body portion 2 preferably of aluminum or aluminum alloy, and a plurality of abrasive particles 3 distributed throughout said body portion of the plate. The abrasive particles may be of relatively small di-

5 mensions, as shown in the enlarged view in Figure 4, or larger particles 4 may be used as illustrated in Figure 5, wherein single particles are of a size to extend substantially throughout the 10 full height of the plate and be exposed on each surface thereof. The plate may also be of the form shown in Figures 6 and 7, wherein a composite plate 5 is illustrated having pre-formed blocks 6 of abrasive material comprising abrasive 15 particles held in a binder formed of abrasive material, such blocks preferably being of a size of the full height of the plate and being held within the body of the plate 1 formed of aluminum or aluminum alloys. It will be noted 20 that the plate shown in Figure 6 presents at its respective longitudinal edges a larger extent of abrasive material than of exposed body metal, and that the edges are smooth and not ragged. This construction avoids the fracturing of the 25 wear edge of the plate and introducing hazards when such plates are used for pedestrian traffic. It has been found desirable in forming plates of the type illustrated in Figure 6 to have the transverse elements of the plates of lesser width than the longitudinal elements. Thus the transverse 30 metal strips 8 may be of a width of one fourth of an inch when the longitudinal strips 9 are formed of a width of one half inch. It is of less importance as to the width of the transverse strips 35 10 over the intermediate areas of the plate, but by having all of the transverse strips of substantially uniform width, a better appearance is brought about and standard sizes of composite blocks may be used in the production of the plate structures.

35 The sprue passageways connecting with the plate proper, when communicating with the ends of the casting cavity, have the disadvantage of having a long path of travel to reach the central 40 areas of the plate and the loss of heat may in some instances be so great as to cause porosity at such central areas, or on the other hand the rate of flow may be sufficiently strong to displace particles of abrasive material disposed in the casting 45 cavity preliminary to the pouring of the body metal of the plate. In order to avoid displacement of the abrasive material and excessive cooling of the metal before it has reached its final position within the mold cavity, it has been found 50 desirable to supply the metal for the body portion of the plate through sprue cavities of the type shown in Figure 1 wherein multiple sprue passageways are provided. The mold used is preferably a sand mold, the flask 11 having a cope portion 55 12 and a drag portion 13. The casting cavity 14 for the plate is formed partly in the sand of the cope and drag portions substantially equally above and below the parting line 15. It has been found desirable to have a plurality of 60 pouring passageways, and for a plate of the size illustrated in Figure 1, wherein the plate is of a width of seven inches and a length of approximately thirty-six inches and of a thickness or height of three eighths of an inch, to provide approximately three points for the introduction of 65 the metal for the body, such metal being preferably, as stated, of aluminum or aluminum alloys. Preliminary to assembling the mold, the particles of abrasive material 3 are inserted therein 70 and the pouring passageways are formed through the material in the cope, such passageways preferably having a large bowl-like opening 16 to receive a substantial supply of metal and the bottom of such bowl-like area being connected by a 75 series of small passageways 17, in the instance

shown four in number, such passageways being inclined slightly outwardly and having at their lower ends flared areas 18 so as to provide for a series of relatively small passageways for the entrance of the metal into the casting chamber, such passageways being spaced from each other a sufficient distance to prevent interference of the metal streams entering the casting cavity and having a gentle rate of flow yet a relatively high rate of supply of metal to the casting cavity. In this manner the more fluent metal substantially free of oxide particles reaches the casting cavity at a plurality of points, in the instance shown at twelve spaced points closely adjacent the central area of the plate, and the flow of metal reaches all portions of the plate while still in free flowing condition so that porous areas are entirely avoided and a product of substantially uniform characteristics throughout is formed.

20 Where blocks of material are used as shown in Figure 6, the position of the multiple pouring sprue passageways 17 is arranged so that the flared openings 18 at the base of such passageways are at points intermediate the blocks so that the metal of the body will flow through the intersecting passageways forming the various bars 8, 9 and 10, heretofore referred to. Upon the removal of the casting from the sand mold, the excess metal will be detached from the surface of the plate by fracturing the same and later grinding or cutting away any residual portions projecting therefrom.

25 The plates, when formed in the manner set forth, will exhibit a remarkably uniform distribution of abrasive material throughout the plate 30 body, as to all the surfaces thereof, including the edge portions which are subjected to the highest degree of wear.

35 In instances where extraordinarily heavy traffic takes place, as in large cities having loading platforms for railways or other vehicles, stores, and thoroughfares for pedestrian traffic wherein stairs or ramps or the like are utilized, the plate 40 may be formed in the manner shown in Figures 6 and 7. Where stair treads are necessary for 45 such thoroughfares, the heaviest wear occurs at the exposed outer edge of the wear plate, and in such instances the pre-formed blocks are closely set, those at the edges particularly having a small edge of separation from each other and presenting a substantially uniform area of abrasive surface over the entire exposed wearing edge of 50 the plate.

55 In all instances, whether the plates are the type illustrated in Figures 1 to 5, or in 6 and 7, it will be found that the rate of wear on the aluminum or aluminum alloy forming the body of the plate is sufficiently greater than the rate of wear on the abrasive material to insure at all times a difference in the level of the body material and the abrasive material. Thus, plates of 60 this character will present abrasive areas having a slight elevation above the remaining supporting surface of the plate, and in the case of rectangular blocks being utilized, as shown in Figure 6, 65 such projecting edges of abrasive material will be exposed at right angles to each other in both transverse and longitudinal directions, and thus slipping in any direction will be resisted to a higher degree than where such uniformity of 70 positioning of such non-slipping areas is not provided.

75 It will be noted that when aluminum is utilized as the body portion of the plates, the high shrinkage characteristics of aluminum serve to provide

5 a surface for the body of the plate slightly below the surface of the abrasive material incorporated therein immediately upon the cooling of the cast metal plate, and this relative positioning of the aluminum body below the plane of the abrasive material is maintained throughout the life of the 10 plate by reason of the greater wear-resisting qualities of the abrasive. The relation of the abrasive material and the aluminum body portion is such that the firm engagement of the body with the adjacent abrasive surface will be of a very firm character. However, with certain 15 types of material it may be desirable to form channels 21 in the abrasive blocks with which key-ways 22 of aluminum will be engaged after the casting operation is completed, as shown in Figure 8.

20 There is no tendency whatsoever of the aluminum and the abrasive particles to crumble or disintegrate at the points of juncture, such as is present when metals of other types are utilized, and there likewise is no tendency toward deformation of either the blocks of abrasive material or of the aluminum body portion under heavy 25 duty service conditions.

20 Other modes of applying the principle of my invention may be employed instead of those explained, change being made as regards the structure herein disclosed, provided the means stated by any of the following claims or the equivalent 30 of such stated means be employed.

I therefore particularly point out and distinctly claim as my invention:

35 1. A wear plate for stair treads and the like, having in combination a plurality of pre-formed elements of wear-resisting material, embodying abrasive fragments, of the full height of the plate structure and a web of aluminiferous material of like height interengaged with said units over lateral surfaces thereof.

40 2. A wear plate for stair treads and the like, having in combination a plurality of spaced pre-formed rectangular blocks of wear-resisting material, embodying abrasive fragments, of the full height of the plate structure and a web of aluminiferous material of like height interengaged with said units intermediate the surfaces of adjacently positioned blocks.

45 3. A wear plate for stair treads and the like, having in combination a plurality of spaced pre-formed rectangular blocks of abrasive wear-resisting material of the full height of the plate structure and a web of aluminiferous material of like height interengaged by means of recesses and projections with said units intermediate the surfaces of adjacently positioned blocks.

50 4. A wear plate comprising a cast aluminum

metal body with wear-resisting elements embodying abrasive fragments engaged therein and distributed at intervals throughout said body, the metal of the body through shrinkage having an outer surface lying below the plane of the outermost abrasive elements. 5

5 5. A wear plate comprising a cast aluminum metal body with wear-resisting elements embodying abrasive fragments engaged therein and distributed at intervals throughout said body, the metal of the body through shrinkage having an outer surface lying below the plane of the outermost abrasive elements and being so maintained through relative wear ratio between said aluminum metal and said abrasive elements. 10

10 6. A wear plate comprising a body portion formed of a metal of high crystallization shrinkage and high heat transfer characteristics, of which the chief constituent is aluminum, with a plurality of abrasive wear-resisting fragments engaged therein and distributed throughout said body with exposed surfaces of said fragments appearing at intervals on at least one surface of such plate. 15

15 7. A wear plate comprising a body portion formed of a metal of high crystallization shrinkage and high heat transfer characteristics, of which the chief constituent is aluminum with a plurality of abrasive wear-resisting fragments engaged therein and distributed throughout such 20 body and with exposed surfaces of said fragments appearing at intervals on the marginal and upper and lower surfaces of said plate. 25

20 8. A wear plate comprising abrasive wear-resisting fragments in spaced relation to each other held firmly in a matrix and distributed throughout the same, such matrix formed of a metal of which the chief constituent is aluminum, such metal being of less wear-resisting capacity than said abrasive fragments and characterized by high 30 crystallization shrinkage whereby permanent engagement with said fragments is provided. 35

35 9. A wear plate comprising abrasive wear-resisting fragments in spaced relation to each other held firmly in a matrix formed of a metal of which the chief constituent is aluminum, such metal being of less wear-resisting capacity than said abrasive fragments and characterized by high 40 crystallization shrinkage whereby permanent engagement with said fragments is provided, such 45 fragments being distributed throughout said plate and being exposed on all marginal and upper and lower surfaces whereby four tread plate edges are provided through reversal and rotation of said plate. 50
